COMBINED PORTABLE RADIO AND CASSETTE PLAYER

Kikuo Ohta, Katano, Osaka, and Toshimasa Akazawa,
Yao, Osaka, Japan, assignors to Matsushita Electric
Industrial Co., Ltd., Kadoma, Osaka, Japan

Filed Oct. 30, 1974, Ser. No. 519,176

Claims priority, application Japan June 25, 1974

Term of patent 14 years

Int. Cl. D14—03

U.S. Cl. D56—4 B

FIG. 1

FIG. 2

FIG. 1 is a front, top and right side perspective view of a combined portable radio and cassette player showing our new design; and

FIG. 2 is a rear, bottom and left side perspective view. The lower front structure of the combined radio and cassette player is symmetrical.

We claim:

The ornamental design for a combined portable radio and cassette player, as shown and described.
